[57] CLAIM

The ornamental design for a portable abrasive conditioning and cleaning machine, as shown and described.

DESCRIPTION

FIG. 1 is a front elevational view of a portable abrasive conditioning and cleaning machine, showing my new design;
 FIG. 2 is a left side view thereof;
 FIG. 3 is a rear view thereof;
 FIG. 4 is a right view thereof;
 FIG. 5 is a top view thereof; and,
 FIG. 6 is a bottom view thereof.
 The broken lines are for purposes of illustration and form no part of the claimed design.
